(57) **CLAIM**

The ornamental design for a rear combination lamp for automobiles, as shown and described.

DESCRIPTION

FIG. 1 is a front view of the rear combination lamp;

FIG. 2 is a plan view of the rear combination lamp;

FIG. 3 is a left side view of the rear combination lamp; and,
FIG. 4 is a front perspective view of the rear combination lamp.

The portions in broken lines represent environmental structure and form no part of the claimed design.
